T-SHAPED HOLLOW FILE

James A. Coon, 929 Drever St., West Sacramento, Calif.
95691, and Elwin Theobald, 4631 Solano Way, Fair
Oaks, Calif. 95628

Filed Mar. 13, 1970, Ser. No. 21,900

Term of patent 14 years

Int. Cl. D8—05

U.S. Cl. D8—90

FIG. 1

FIG. 2

FIG. 3

FIG. 4

FIG. 5

FIG. 1 is an enlarged end elevational view of our new design for a T-shaped hollow file;

FIG. 2 is a top plan view thereof;

FIG. 3 is a side elevational view as viewed from the left in FIG. 1;

FIG. 4 is a bottom plan view thereof; and

FIG. 5 is a side elevational view as viewed from the right in FIG. 1.

We claim:

The ornamental design for a T-shaped hollow file, substantially as shown.
